Des. 237,725
Patented Nov. 18, 1975

237,725

PLAY SLIDE

Frederic Gregg Loeser, 160 E. Rock Road,
New Haven, Conn. 06511

Filed Apr. 6, 1973, Ser. No. 348,469

Term of patent 14 years

Int. Cl. D21—03

U.S. Cl. D34—5 E

Fig. 1.

Fig. 2.

Fig. 3.

Fig. 4.

FIG. 1 is a front elevational view of the play slide showing my new design;

FIG. 2 is a top plan view of the play slide shown in FIG. 1;

FIG. 3 is a side elevational view looking toward the play slide from the left of FIG. 1;

FIG. 4 is a side elevational view looking toward the play slide from the right of FIG. 1;

FIG. 5 is a rear elevational view of the play slide shown in FIG. 1;

FIG. 6 is a bottom plan view of the play slide shown in FIG. 5; and

FIG. 7 is a perspective view of the play slide shown in FIG. 1.

I claim:

The ornamental design for a play slide, as shown and described.
